(57) **CLAIM**

The ornamental design for an inflating gun for a compressor, as shown and described.

DESCRIPTION

FIG. 1 is a top-front-left perspective view of an inflating gun for a compressor showing my new design;

FIG. 2 is a top plan view thereof;

FIG. 3 is an elevated front view thereof;

FIG. 4 is an elevated rear view thereof;

FIG. 5 is a bottom plan view thereof;

FIG. 6 is an elevated right view thereof; and,

FIG. 7 is an elevated left view thereof.
